UNITED STATES PATENT OFFICE.

JOSEPH T. THOMPSON, OF VERONA, ASSIGNOR OF ONE-HALF TO EDWARD BARNARD, OF ROME, NEW YORK.

RAKE.

SPECIFICATION forming part of Letters Patent No. 416,763, dated December 10, 1889.

Application filed August 20, 1889. Serial No. 321,346. (No model.)

To all whom it may concern:

Be it known that I, JOSEPH T. THOMPSON, a citizen of the United States, residing at the town of Verona, in the county of Oneida and State of New York, have invented a new and useful Rake, of which the following is a specification.

This invention relates to rakes; and it has for its object to provide an improved self-cleaning attachment which may be readily applied to the head of any ordinary hand-rake, and which shall be simple in construction, durable, and easily applied or detached, as occasion may require.

A further object of the invention is to so construct the said self-cleaning attachment that it shall serve for the purpose of cutting and pulling weeds and the like when desired. The invention consists in the improved construction of the said attachment, which will be hereinafter fully described, and particularly pointed out in the claims.

In the drawings hereto annexed, Figure 1 is a perspective view of my improved self-cleaning attachment for hand-rakes. Fig. 2 is a plan view of the same. Fig. 3 is a detail perspective view of one of the links or clasps by means of which the device is secured to the rake-head. Fig. 4 is a perspective view showing the head and a portion of the handle of a rake having my improved self-cleaning attachment.

Like numerals of reference indicate like parts in all the figures.

My improved self-cleaning attachment consists of a strip 1, of metal, preferably steel, which may be used in the form of sheet metal of suitable thickness. The front edge of the strip 1 is provided with a series of teeth 2, 2, which may be triangular or any other suitable shape. The sides of the said teeth may be ground down, so as to form sharp cutting edges 3.

The strip 1 is provided with a series of perforations 4 to admit the teeth 5 of a rake-head 6 of ordinary construction. The perforations 4 should be of a size to permit the rake-teeth to slide freely therein, thus enabling the strip 1 to move freely vertically upon the teeth of the rake-head.

7 7 designate a pair of links or clasps, which are secured to the upper side of the strip 1 by means of bolts or rivets 8. Each of the said links or clasps is constructed, preferably, of a flat strip of spring metal bent into the shape of an oblong link and having its meeting ends cut off diagonally, as shown at 9 9, so as to form practically an oblique slot 10 at the upper end of the said link. Two or more of these links or clasps may be secured to the upper side of the strip 1 in the manner described, and it will be seen that by turning the said links or clasps until the oblique slots 10 are in alignment with the rake-head, the device may be readily adjusted in position by simply springing the links open to receive the rake-head. The links are then turned to a position in alignment with each other and with the rake-head, thus placing the slots 10 obliquely with relation to the latter, and thus retaining the device securely in position upon the rake-head.

The operation and advantages of my invention will be readily understood from the foregoing description, taken in connection with the drawings hereto annexed.

It will be seen that the tendency of the strip 1 is to move in an outward or downward direction upon the rake-teeth, which are thereby kept clear of rubbish. By pushing the rake in a forward direction the teeth upon the front edge of the strip 1 will act as cutters to chop or cut weeds and the like. The device is exceedingly simple in construction, and it may in a moment's time be attached to or removed from any hand-rake of ordinary construction.

Having thus described my invention, what I claim, and desire to secure by Letters Patent, is—

1. A cleaning attachment for hand-rakes, consisting of a strip having perforations to receive the rake-teeth and provided at its edge with teeth-cutters, substantially as and for the purpose set forth.

2. A self-cleaning attachment for hand-rakes, consisting of a metallic strip having a front cutting-edge and provided with perforations to admit the rake-teeth, substantially as set forth.

3. The combination, with a rake-head, of a vertically-sliding cleaning-strip having cutters at its front edge, substantially as set forth.
5. 4. A cleaning attachment for hand-rakes, consisting of a vertically-perforated strip having the obliquely-slotted links or clasps attached to its upper side, substantially as set forth.
10. 5. The combination, with the vertically-perforated cleaning-strip, of the obliquely-slotted links or clasps secured pivotally to the same by means of bolts or rivets, substantially as set forth.
15. 6. The herein-described self-cleaning attachment for rakes, consisting of a metallic strip having a series of vertical perforations, provided at its front edge with teeth or cutters, and having the obliquely-slotted links or clasps secured pivotally to the upper side, substantially as set forth.
20. 7. The combination, with the cleaning-strip for hand-rakes having a series of perforations to admit of the rake-teeth, of the spring links

or clasps for securing the same detachably to the rake-head, said links or clasps being composed of strips of spring metal having diagonal meeting ends, whereby oblique slots are formed in the upper ends of said links, the latter being secured pivotally to the upper side of the cleaning-strip, substantially as and for the purpose set forth.

8. The combination, with a hand-rake, of a cleaning-strip having perforations, whereby it is mounted to slide vertically upon the rake-teeth, said cleaning-strip being provided at its front edge with teeth or cutters and having obliquely-slotted spring clasps or links secured pivotally to its upper side, whereby it may be connected detachably with the rake-head, substantially as set forth.

In testimony that I claim the foregoing as my own I have hereto affixed my signature in presence of two witnesses.

JOSEPH T. THOMPSON.
